LOOM SHUTTLE

Philip L. Spencer, Millbury, Mass., assignor to
 Watson-Williams Manufacturing Company,
 Millbury, Mass., a corporation of Massachusetts

Application November 13, 1939, Serial No. 304,033

7 Claims. (Cl. 139—211)

This invention relates to loom shuttles of the type in which the bobbin is mounted on a pivoted spindle.

It is the general object of my invention to provide improved means for holding a bobbin securely on a shuttle spindle when the spindle is lowered to running position but allowing easy removal of the bobbin when the spindle is raised.

A further object of my invention is to simplify the construction and reduce the number of parts in such devices, with resultant and important savings in time, labor and material.

My invention further relates to arrangements and combinations of parts which will be herein-after described and more particularly pointed out in the appended claims.

Preferred forms of the invention are shown in the drawing, in which

Fig. 1 is a partial plan view of a shuttle with my improvements embodied therein;

Fig. 2 is a side elevation of the same portion of the shuttle, but partly in section along the line 2—2 in Fig. 1;

Fig. 3 is a side elevation, partly in section, of the corresponding portion of the shuttle blank;

Fig. 4 is a transverse sectional view, taken along the line 4—4 in Fig. 3;

Fig. 5 is a partial side elevation of a shuttle spindle;

Fig. 6 is a side elevation of a bobbin-holding spring;

Fig. 7 is a plan view of the spring, looking in the direction of the arrow 7 in Fig. 6;

Figs. 8 and 9 are transverse sectional views, taken along the lines 8—8 and 9—9 in Fig. 7 respectively; and

Fig. 10 is a plan view of a slightly modified construction.

Referring to the drawing, I have shown one end portion of a shuttle blank 10 having the usual longitudinally extending central recess 11 to receive a bobbin B. The recess 11 is also extended toward one end of the shuttle as indicated at 12 and 14 in Fig. 3, the portion 14 being slightly narrower and deeper than the portion 12 for purposes to be described.

The shuttle blank 10 also has a longitudinal slot 15 overlying the recesses 12 and 14 and slightly narrower than either of said recesses, thereby providing shoulders 16 which confine a U-shaped bobbin-holding spring 20 from upward movement. The rear or closed portion of the spring 20 is snugly fitted in the narrower recess 14 and is retained in position by a cross-pin 22.

The spring 20 is provided with outwardly spaced portions 24 (Fig. 7) having inwardly offset end flanges 25, cut away as indicated at 26 in Fig. 8 to receive the barrel of the bobbin B.

5 A spindle 30 is provided for the bobbin B and comprises a blade portion 31, which may be either solid or split, a flange 32 against which the bobbin B is seated, a cylindrical shank portion 33, and a butt or head 34 having a transverse bearing opening 35. The head 34 fits closely between the sides of the closed end portion of the spring 20 and the spindle is pivotally retained in position by the same crosspin 22 which locks the spring in the shuttle blank.

10 The spaced side members of the U-shaped spring 20 are provided with upper and lower, inwardly-projecting cam portions 40 and 41 (Fig. 9). When the spindle 30 is in the raised or inoperative position shown in dotted lines in Fig.

15 2, the shank portion 33 of the spindle overlies and is supported by the upper cam projections 40. As the spindle is swung downward, the shank portion 33 engages the projections 40 and spreads the spaced end portions 24 of the spring 20 further apart, to permit entrance of the flange 32 on the spindle 30 and of the flange 42 on the bobbin B between the inwardly offset flanges 25 of the spring portions 24.

20 As the spindle reaches its lowered or running position, the shank 33 is received in the substantially circular recess 43 (Fig. 3) between the side members of the spring 20 and is yieldingly held by the projections 40 and 41 from either upward or downward displacement. At the same time 25 the end face 44 of the spindle butt or head 34 engages the closed end of the spring 20, as shown in Fig. 2, thus additionally and accurately determining the running position of the spindle.

The extra depth of the recess 14 allows the spindle head to turn, and the extra width of the recess 12 allows the spring to be expanded sideways by the shank 33.

30 I have thus provided a construction embodying a pivoted spindle, a bobbin-clamping device, and spindle-positioning means, which entire construction comprises only two parts, namely, a spindle and a U-shaped spring.

I have also provided a construction by which the spindle is firmly held in either raised or lowered position and by which the spring is securely locked in the shuttle blank, all without the use of any additional parts, except the usual crosspin 22. My improved construction is thus extremely simple and economical to manufacture and very reliable in use.

In Fig. 10 I have shown a slight modification in the shape of the holding ends of the spring 50, said ends being provided with a series of grooves 51 to receive a plurality of rings 52 on the butt of a bobbin B' of a type commonly used in automatic weft-replenishing looms.

It will be understood that the holding ends of the spring may be otherwise modified to adapt them to use with additional types of bobbins.

Having thus described my invention and the advantages thereof, I do not wish to be limited to the details herein disclosed, otherwise than as set forth in the claims, but what I claim is:

1. In a loom shuttle, in combination, a spindle pivoted in said shuttle, and a spindle-holding spring having spaced bobbin-holding arms which are provided with cam portions engaged by said spindle and separating said arms to receive a bobbin as said spindle is moved downward, said arms being released by said spindle to move inward and clamp the bobbin as the spindle reaches its lowered running position and said cam portions being inwardly positioned and yieldingly supporting said spindle when the spindle is in raised position.

2. In a loom shuttle, in combination, a U-shaped spindle-holding spring longitudinally and vertically fixed in said shuttle but having spaced bobbin-holding arms yieldingly movable horizontally outward from holding position, a spindle pivotally mounted in said shuttle between the sides of said U-shaped spring near its closed end, and said movable arms having cam projections engaged and forced apart by said spindle as said spindle is moved downward, whereby said arms are spread apart to receive a bobbin placed on said spindle and said cam projections being inwardly positioned and yieldingly supporting said spindle when the spindle is in raised position.

3. In a loom shuttle, in combination, a U-shaped spindle-holding spring longitudinally and vertically fixed in said shuttle but having spaced bobbin-holding arms yieldingly movable horizontally outward from holding position, a spindle pivotally mounted in said shuttle between the sides of said U-shaped spring near its closed end, and said movable arms having cam projections engaged and forced apart by said spindle to bobbin-receiving position as said spindle is moved downward but substantially free of said spindle 50

when the spindle is in extreme raised or extreme lowered position.

4. In a loom shuttle, a pivoted spindle, a U-shaped spindle-holding spring having spaced 5 bobbin-holding arms, and means to secure said spindle and spring in the shuttle, said spindle directly engaging and separating the bobbin-holding arms of said U-shaped spring to receive a bobbin as said spindle is moved from raised to lowered position and said arms being inwardly positioned and yieldingly supporting said spindle when the spindle is in raised position.

5. In a loom shuttle, a pivoted spindle, a U-shaped spindle-holding spring having spaced 15 bobbin-holding arms, and means to secure said spindle and spring in said shuttle, said spindle directly engaging and separating the bobbin-holding arms of said U-shaped spring to receive a bobbin as said spindle is moved from raised to lowered position and releasing said arms to clamp 20 said bobbin when said spindle is in lowered running position and said arms being inwardly positioned and yieldingly supporting said spindle when the spindle is in raised position.

25 6. In a loom shuttle, a pivoted spindle, a U-shaped spindle-holding spring having spaced bobbin-holding arms, and means to secure said spindle and spring in said shuttle, said spindle directly engaging and separating the bobbin-holding 30 arms of said U-shaped spring to receive a bobbin as said spindle is moved from raised to lowered position, and said spring constituting the sole means for holding said spindle selectively in raised or lowered position and for holding said bobbin on said spindle.

35 7. In a loom, a shuttle having a longitudinal recess, a U-shaped bobbin-holding spring fitting 40 said recess and held from vertical displacement by inwardly projecting flanges above said recess, a spindle mounted between the sides of said spring, a single means to pivot said spindle in said shuttle and to lock said spring in said recess, cam means on said spring engageable by said spindle and effective to hold said spindle yieldingly in raised or lowered position, and a portion 45 of said spring directly engaging a butt portion of said spindle to accurately determine the lowered running position of said spindle.

PHILIP L. SPENCER.
